UNITED STATES PATENT OFFICE

HARLEY H. WOLFE, OF DAYTON, OHIO, ASSIGNOR TO THE DAYTON PUMP & MFG. COMPANY, OF DAYTON, OHIO, A CORPORATION OF OHIO

DESIGN FOR A LIQUID DISPENSING PUMP

Application filed May 12, 1932. Serial No. 43,777. Term of patent 7 years.

To all whom it may concern:

Be it known that I, HARLEY H. WOLFE, a citizen of the United States, residing at Dayton, in the county of Montgomery and State of Ohio, have invented a new, original, and ornamental Design for a Liquid Dispensing Pump, of which the following is a specification, reference being had to the accompanying drawing forming a part thereof.

In the accompanying drawing:

Figure 1 is a perspective view of the liquid dispensing pump showing my new design;

Figure 2 is a top plan view thereof;

Figure 3 is a section taken at line 3—3 of Figure 1;

Figure 4 is a section through the top of the pump; and

Figure 5 is a section through the base of the pump.

I claim:

The ornamental design for a liquid dispensing pump as shown.
